RESTAURANT SIGN

George L. Olson, Toms River, N. J.

Application October 4, 1949, Serial No. 5,301

Term of patent 14 years

(Cl. D1—12)

To all whom it may concern:

Be it known that I, George L. Olson, a citizen of the United States, residing at Toms River, in the county of Ocean and State of New Jersey, have invented a new, original, and ornamental Design for Restaurant Signs, of which the following is a specification, forming part thereof.

Fig. 1 is a front elevational view of a restaurant sign, showing my new design.

Figure 2 is an end elevation thereof.

Figure 3 is a horizontal sectional view taken on the line 3—3 of Figure 1.

I claim:

The ornamental design for a restaurant sign, as shown.

GEORGE L. OLSON.
